UNITED STATES PATENT OFFICE

CLAUDIUS DORNIER, OF FRIEDRICHSHAFEN-ON-THE-BODENSEE, GERMANY, ASSIGNOR
OF ONE-HALF TO THE FIRM: DORNIER METALLBAUTEN GESELLSCHAFT MIT BE-
SCHRÄNKTER HAFTUNG, OF FRIEDRICHSHAFEN, GERMANY

METAL ENVELOPE FOR AIRCRAFT PLANES

Application filed November 27, 1922, Serial No. 603,638, and in Germany December 12, 1921.

My invention has reference to the supporting planes of aircraft, and it particularly refers to all metal planes, one of its objects being to provide novel means for connecting the several strips or webs of sheet metal to each other and to the supporting beams, in pursuance whereof a great stability and resistibility is imparted to the planes, while the thickness of the supporting and fastening instrumentalities may be greatly reduced.

10 The edge portions of the several sheets which are shaped in accordance with the configuration of the planes or wings, are turned upwards or downwards in a manner already suggested heretofore, so as to impart a kind of expanded U-sectional or channel shape to said sheet, provision being made to connect the bent edges of said sheets by embracing them with substantially channeled sheet metal members which are connected to said rims by rivets, bolts or the like.

15 The fins or ribs produced in this manner have heretofore been ordinarily arranged to extend in the direction of flight, and in such a manner that on one surface they were directed outwardly, and on the other surface inwardly, or they were arranged to protrude outwards on both surfaces. In this arrangement and construction of the projecting ribs or fins produced in this manner, there was the difficulty of securing the envelope to the front beam, the so-called nose of the supporting plane, the said front beam as well as the other beams in view of the low resistive qualities of such envelopes opposed to the forces 20 acting upon the plane in the longitudinal direction of the beams necessitating a very strong and heavy material and construction in view of the arrangement of the ribs or fins in the direction of flight.

25 In accordance with my invention these drawbacks are overcome by making provision to arrange the metal sheet constituting the covering envelope of the supporting planes in such a manner that the ribs or fins produced at the joints of the sheets extend transversely to the direction of flight, that is to say, in parallel to the front and rear edges of the supporting plane. In this case the connection of the joints at the front beam or nose

of the supporting plane can be effected in the same manner, as with the other metal sheets, by bending the marginal portions outwards and connecting them to the beam by rivets, screws or the like. In the case of metal sheets of very thin material the fin or fins produced by the supporting beam and the turning over of the edges of the metal sheets, as well as the fins or ribs formed on the top and bottom may be bridged over by suitably formed and figured metal sheets, so as to allow of using a comparatively small number of strong rivets in place of a large number of weak rivets.

30 In view of the large resistance presented to forces acting upon it by a longitudinally finned supporting plane of the kind referred to, the supporting beams employed may be comparatively thin and of light material, and they may be replaced by a succession of struts of light weight or by strips of sheet metal which are inserted between the turned-over edges of the sheets of metal and are riveted thereto. The drawbacks, if any, of such ribs or fins running transversely to the direction of the air current, from an aero-dynamic point of view, are of no material importance, and may be rendered absolutely insignificant by providing such projecting ribs on the pressure side of the wings only where the velocity of the air is known to be comparatively small, and is even reduced to zero at certain points or with some shapes even takes the direction opposite to the flight, while on the other side of the supporting surface the edges of the metal sheets are turned inwards, and are secured by rivets to the combination of struts or to the sheet metal strips. Also in such cases there is the possibility of readily assembling and repairing the plane by first constructing the inner joints, and by subsequently closing the supporting plane by the metal sheets with outwardly positioned joints.

35 In a preferred construction according to my invention the longitudinal supporting beams are utilized by using the flanges of these beams to laterally engage the turned-over edges of the metal sheets therewith, while with the outwardly positioned ribs the

flanges of the longitudinal beams are embraced by the U-shaped figured metal sheets. Every single metal sheet may consist of several separate strips which are connected to the figured sheets of metal running transversely thereof in the same manner as the individual sheets of metal by the turning over of the edges and by securing them to the transverse sheets by rivets or screws. In the 10 case of injury to any of these strips the particular strip may be easily removed and exchanged in the same manner as the entire sheet by loosening the rivets or screws. If mere struts are used for stiffening purposes 15 they are secured to the joints of the sheets so as to serve the purpose of flanges. The combination of struts in such cases may extend in the plane of the joints of the sheets and as a frame work between two adjoining sheet joints. Instead of struts recessed sheet 20 metal webs may obviously also be used.

The invention will be more fully described with reference to the accompanying drawing showing by way of example several forms of embodiment of the principles of my invention. In the drawing—

Figures 1, 3 and 5 are diagrams of cross sections;

Figures 2 and 4 are diagrammatic representations of sections on lines A—A and B—B respectively of Figures 1 and 3.

In the form of construction shown by way of example in Figures 1 and 2 the covering envelope consists of webs of sheet metal α 35 running in parallel to the front and rear edges of the supporting plane, the edges of the sheet metal webs being turned up outwardly, and their intermediate portion corresponding to the distance of the series of struts b which form the panel work of the longitudinal beams. The upturned edges of the webs of sheet metal are embraced by 40 channeled strips of sheet metal c , and the struts b are introduced between these upturned edges of the webs α , so that these edges constitute the booms for the series of struts. The edges are connected by rivets or 45 the like with the strips c placed thereon and the struts.

In the modifications shown as an example 50 in Figures 3 and 4 the rib occurring at the front edge of the supporting plane as shown in Figures 1 and 2, is dispensed with in view of the fact that the sheet metal web α' constituting the front or nose portion of the supporting plane possesses the necessary width 55 and thickness to present sufficient resistance to strains acting thereon. Also the ribs upon the upper side of the supporting surface of 60 the plane have been done away with by turning the edges of the sheet metal webs inwards, so as to produce a plane outer surface. These edges are secured by rivets to the recessed or perforated sheet metal strips d serving 65 as longitudinal supporting beams. On

the bottom side, however, the edges are turned outwards, and are united, in the manner shown in Figures 1 and 3, to each other and to the sheet metal strips d by disposing thereon correspondingly formed metal sheets c 70 and securing them by rivets or screws.

Instead of sheet metal strips d I may obviously also use series of struts or the like as shown in Figures 1 and 3, and in place of the series of struts c of Figures 1 and 3 sheet 75 metal strips d may be used.

In the modification disclosed in Figure 5 each single sheet metal section situated between the longitudinal supporting beams is composed of several strips in a manner similar to the connection of the several webs to each other, the terminal strips of such composite sections constituting at the same time the top and bottom booms of the pairs of longitudinal supporting beams, so as to transform them into box girders. In case the sheet metal strips are formed of very thin walled material light transverse supporting beams acting as wing ribs and serving as supports for the composite sheet metal sections may be 80 employed for the maintaining of the shape. This kind of composite outer envelope may also be arranged in such a manner that the ribs upon one side of the supporting plane are disposed at the inside similar to the construction shown in Figure 3 of the drawing. 85

In order to show the joints of the metal sheets with greater clearness they are shown on the drawing on a greatly enlarged scale as compared with the dimensions of the supporting plane.

I wish it to be understood that my invention is not restricted to the particular embodiments herein shown and described by way of example, nor to the particular mode of utilization enumerated, the scope of my invention admitting of various alterations and embodiments to adapt the invention to different conditions of application; and the language of this specification and claims is 100 not intended as a limitation to the scope of my invention.

I claim:—

1. A wing construction for airplanes comprising an envelope composed of a plurality 115 of solid sheet metal strips having stiffening means extending outwardly of the surface and longitudinally of the wing, said means constituting air resistance elements acting to increase the carrying capacity of the airplane when in flight.

2. A wing construction for airplanes comprising an envelope composed of a plurality of solid sheet metal strips, and stiffening ribs extending outwardly of the surface of the envelope and longitudinally thereof to resist transverse breaking stresses, said ribs being formed to offer slight air resistance during flight whereby the carrying capacity of the airplane when in flight is increased. 120 125 130

3. A wing construction for airplanes comprising an envelope composed of a plurality of metal sheets running transversely to the line of flight and having outwardly turned flanges along their meeting edges forming stiffening ribs and means for connecting the sheets together, and channel means engaging about said flanges and constituting longitudinal beams for further resisting the transverse breaking stresses.
- 10 4. A wing construction for airplanes comprising an envelope composed of a plurality of metal sheets running transversely to the line of flight, stiffening ribs extending outwardly on one of the surfaces of the envelope and inwardly on the other, and means for connecting the sheets together.
- 15 5. A wing construction for airplanes comprising an envelope composed of a plurality of metal sheets running transversely to the line of flight and having outwardly turned flanges along their meeting edges forming stiffening ribs and means for connecting the sheets together, bracing means extending 20 within such envelope and between the meeting flanges of pairs of adjoining sheets, and means for connecting said flanges and bracing means together.
- 25 In testimony whereof I affix my signature.
